PORTABLE TYPEWRITER

Giuseppe Prezioso, Yverdon, Switzerland, assignor to E. Paillard & Cie, S. A., Yverdon, Switzerland

Application July 20, 1935, Serial No. 32,464
In Germany July 30, 1934

1 Claim. (Cl. 197—186)

This invention relates to portable typewriters and in particular to that type in which the base frame is stiffened and rendered more rigid by a base plate firmly attached to said base frame. 5 It has been proposed to produce a rigid base frame for instance by pressing and drawing sheet metal to form a base plate and the side walls of the base frame.

In such known constructions the side parts of 10 the base frame and the base plate form a rigid structure.

According to the present invention the base plate is removably secured to the side walls of the base frame in such a manner that all the 15 parts of the typewriter needing adjustment are readily accessible.

To render the base frame still more rigid the base plate is provided with upturned edges. The base plate forms part of the casing of the typewriter.

The base plate is secured to the side walls of the base frame by means of screws which are easily accessible and which are used for several purposes. For instance the screws may serve 25 as supporting feet on which the typewriter rests moreover the screws are used as hinges or fixing elements to secure the cover of the typewriter to the upstanding edges of the base plate. The cover not only protects the typewriter against 30 dust etc. but when placed upon the base plate it fits tightly against the upper part of the typewriter so as to secure all the movable parts in their respective positions as for instance the type levers, the paper platen, the paper carriage, 35 the inking band rollers and so on.

By the particular construction and arrangement of parts, I attain a portable typewriter of but small dimensions, but of an efficiency which equals or exceeds that of known typewriter of 40 full size.

In the accompanying drawings is illustrated in largely diagrammatic manner, an example of construction.

- Fig. 1 shows a plan view,
45 Fig. 2 is a perspective view of the machine,
Fig. 3 shows a section of the machine,
Fig. 4 is a longitudinal section,
Figs. 5 and 6 show how the cover is fixed to the machine.
50 The frame of the machine shown in the drawings consists of two pieces or parts 1 and 53 (Figs. 1, 2, 3) which are detachably connected

together by means of four screws 2 passed through slots 3. The front part 1 receives the keys 40 and the type levers 37 whereas the rear part 53 carries the paper carriage, the platen, the carriage feed mechanism etc. The vertical side 5 parts of the frame parts 1 and 53 are connected to one another by means of transverse stays 8, 10, 11 and 12 (Fig. 4) preferably made of light metal, so that the parts 1, 53, 8, 10, 11 and 12 form a rigid construction. The two frame parts 10 1 and 53 are secured to a common base plate 93, which is provided with an edge 30, by means of screws 94 and 95. The screws 94 not only hold the machine on the base plate 93 but they serve as feet when the machine is transported in a 15 vertical position. The multiple use of the screws 94, 95 simplifies the machine.

The cover 97 of the machine fits snugly upon the edge 30 of the base plate 93 (Figs. 3, 4, 5).

The dimensions of the cover 97 are such that 20 the latter lies tightly on the cover 92 fixed to the frame and formed of a piece of sheet metal. The inking band rollers 43, the paper carriage, the type levers etc. are thereby secured in their position and any movement of these parts is 25 obviated. The cover is connected to the base plate by the above mentioned screws 94 and 95 and is provided with holes into which the screws 94 can enter. The heads of the screws 95 which are equally screwed to the edge 30 of the base 30 plate are provided with necks. When the cover 97 is placed on the machine these necks come to lie in slots of said cover. The latter is firmly held by the two hooks 99, which are hinged to the cover and engage over the screws 95 (Figs. 35 5 and 6). The cover is provided with a handle 98 by means of which the entire machine can be carried in one hand.

What I claim is:

In a portable typewriter having an open rectangular base frame, a base plate having a marginal upturned flange, said open rectangular frame fitting snugly between the front and back marginal flange portions, screws passing through the front and back marginal flange portions into 45 the adjacent walls of said frame, a cover over the machine and fitting over said marginal flange, said cover having holes to receive the back screws aforesaid, slots to receive the front screws aforesaid, and latches on the cover to 50 engage the front screws aforesaid.

GIUSEPPE PREZIOSO.
